P. BROWN

MOP HEAD

Filed March 21, 1927

UNITED STATES PATENT OFFICE.

PETER BROWN, OF CHICAGO, ILLINOIS, ASSIGNOR TO O-CEDAR CORP'N, A CORPORATION OF ILLINOIS.

MOP HEAD.

Application filed March 21, 1927. Serial No. 176,947.

This invention relates to a mop head of the type wherein the mop stock in strip form is adapted to be secured to a supporting metal strip or band.

- 5 It is an object of this invention to provide a mop head of this type which may be made in a simple and inexpensive manner, and which is adapted to the purposes of large scale production.
- 10 Other and further important objects and advantages of this invention will be apparent from the following description of an illustrated embodiment of the present invention.

On the drawings:

- 15 Figure 1 is a top plan view of a finished mop head embodying the principles of my invention.

Figure 2 is a top plan view of an unformed mop head showing the forming operation in dotted lines.

Figure 3 is a fragmentary elevational view of Figure 2, and

Figure 4 is a sectional view taken parallel to the plane of the mop head.

25 As shown on the drawings:

The reference numeral 1 indicates a supporting band, preferably formed of a relatively soft metal. In the operation of preparing the metal strip to serve as a supporting band for a mop swatch 2, tongues or

30 prongs 3 are struck up from the band 1 at predetermined spaced intervals. Said tongues 3 serve to engage the band 4 of the mop swatch 2 and also provide slots 5. Said

35 slots 5 are so positioned as to locate the vertices of the triangular ring into which the band 1 is subsequently formed, the weakening of the metal band caused by the slots being sufficient to cause the band to bend naturally at those points, (Figure 2). The ends of the band 1 are bent at right angles thereto as shown at 6 and 7.

40 While the band 1 is still in straight form, the mop swatch 2 which is produced in the form of strips, is laid over said band 1 and the tongues 3 inserted through the hem or band 4 of the mop stock. The tongues 4 are

then bent over against the hem of the mop stock to lie parallel to the band 1.

It should be noted in the case of the tongues 50 located at the vertices of the triangular ring, that said tongues are bent away from the slot 5 instead of over said slots, otherwise the tongues themselves would have to be separately bent during the subsequent bending 55 operation to form the triangular ring.

When the band 1 is in ring form, the ends 6 and 7 lie in abutting relation and are adapted to be secured together and to a socket 8 by means of a bolt 9 passing through the 60 ends thereof. A handle 10 may be threaded or otherwise secured in the socket 8.

It will be appreciated that a mop head such as above described may be made by a few simple mechanical operations, and that therefore the cost of production is considerably less than in the case of mop heads previously made by more elaborate methods. It should also be noted that the various operations in the making of the mop heads are such as 70 admit of quantity production, with the consequent saving that may be realized by a large scale operation.

I am aware that many changes may be made and numerous details of the construction may be varied through a wide range without departing from the principles of this invention, and I therefore do not purpose limiting the patent granted hereon, otherwise than necessitated by the prior art and 80 the appended claim.

I claim as my invention:

A mop head comprising a metal strip having ends bent at right angles thereto, said strip being bent into a triangle with said 85 ends abutting each other, teeth struck out from said strip forming slots for defining the position of the vertices of the triangle and a mop fabric adapted to be engaged by said teeth and to be secured to said strip by 90 being hooked over said teeth.

In testimony whereof I have hereunto subscribed my name.

PETER BROWN.
